CONTAINER FOR BLASTING CAPS

Albert R. Ely and Roscoe B. Smith, Wilmington,
Del., assignors to Hercules Powder Company,
Wilmington, Del., a corporation of Delaware

Application December 27, 1941, Serial No. 424,620

5 Claims. (Cl. 206—3)

This invention relates to the packaging of blasting caps and more particularly to an improved method of packaging fuse blasting caps, and the package produced.

Fuse blasting caps contain a detonating charge pressed into the base or closed end of a shell which then has the other end open to allow the insertion of a safety fuse which is then crimped into place in the open end. In order to fire the cap, the fuse is lighted and allowed to burn and ignite the detonating explosive in the base of the blasting cap. The fuse blasting caps known to the art are closed end copper or aluminum casings having a diameter of between about .22 inch and .25 inch and a length of from about 1½ to 2 inches. The art provides the industry with these blasting caps packaged usually in tin boxes which contain 10, 25 or 100 individual caps. The normal method of packaging blasting caps within the tin boxes is to place each cap in the box with its open end up, i. e., in a position that allows an operator to look down onto the explosive composition in the bottom of the cap. This method is usually adhered to because visual inspection is possible and misfires due to foreign material being in the cap are prevented. However, there is danger experienced in this type package because the explosive charge is exposed and foreign material can fall into the cap. This foreign material may be sparks, ashes, abrasives, liquids or the like and such material may cause premature explosion or misfires, either of which are dangerous in operations.

To overcome such difficulties, it is known to pack the caps with their closed end down. However, such packing is not well thought of by the art, and the very large majority of caps are packed with their open face up.

It is the object of this invention to provide an improved packaging method for packaging fuse blasting caps.

A further object of the invention is to provide an improved container for fuse blasting caps.

A still further object of the invention is to provide a liner for the tin boxes now in use which will allow a safer method of packaging fuse blasting caps.

Another object of the invention is to provide a container for fuse blasting caps which will prevent any foreign material from entering the blasting cap.

Another object of the invention is to provide a container in which blasting caps may be packed by a suitable method to provide inspection thereof, and which is then suitable for insertion into

a tin box in a position which prevents foreign material from entering the open end of the blasting cap but which allows easy removal of individual caps.

Another object is to provide a jig for aiding the packaging of the caps into the liners and container.

Other and further objects of this invention will be apparent upon reading the following description, and an understanding of the drawings attached to the specification.

The objects of this invention have, in general, been accomplished by providing a liner which is adaptable for insertion into a square or rectangular box suitable for packing a plurality of blasting caps. This liner is so designed that the blasting caps may be either packed therein by first placing them into a jig where they are inspected and counted and then transferred to the liner or the caps may be packed into the liner in an upright position, counted and inspected by looking into the open end thereof. The caps and liner are then inserted preferably into a metal container of normal "tin can" construction, but heavy cardboard or the like may be used. The design of the container allows easy removal of the caps and further causes positioning of the caps within the box with their long axes parallel to the bottom and top of the box.

In more particular, the invention consists of a liner of foldable material, such as cardboard or the like, formed to fit into a container, such as a "tin box" or the like, of suitable construction for receiving blasting caps. The liner entirely encloses all of the blasting caps and may have a slit or like opening with foldable flap cover only sufficiently large to permit the discharge of a single blasting cap, or the opening may be any portion or the entire top, which opening also is provided with a cover hinged to an edge of the liner. The container which exposes only a single blasting cap, and that only along its length, is preferred in many instances, but the container having a larger opening discharges caps more easily. In all containers, however, the open ends of the caps are abutted against one side of the box, and thus they are effectively sealed against entrance of any foreign material.

In order to describe the container of this invention in more detail, a description of preferred embodiments thereof is made with reference to the attached drawings in which like numerals refer to like parts, and in which:

Fig. 1 is a perspective view of the tin box with the cover in place;

Fig. 2 is similar to Fig. 1 but without the cover and showing the liner;

Fig. 3 is a perspective view of the container with blasting caps in place and a cap in the act of being discharged from the container;

Fig. 4 is a side elevation view of the container of Fig. 3 with one side cut away to show the arrangement of caps therein;

Fig. 5 is a plan view of the blank forming the liner of Figs. 2, 3 and 4;

Fig. 6 is a perspective view of a form or jig suitable for use as an aid in packing caps into liners and containing a number of caps that have closed ends up but can be reversed;

Fig. 7 is a perspective view of a liner positioned for receiving caps from the jig shown in Fig. 6; and

Fig. 8 is a plan view of the blank forming the liner of Fig. 7.

The blasting cap package, in accordance with this invention, comprises a liner 1 which contains a plurality of fuse blasting caps 2 positioned with their longitudinal axes parallel to the base 3 of the container. The liner 1 is positioned in a supporting tin box 4 which has a closely fitting tin cover 5. In Fig. 1, the tin box has its cover in place, while in Fig. 2, the cover is omitted and the liner 1 exposed.

The liner 1 which fits into the tin box 4 has an opening 6 which opening is coordinated with the long axes of the blasting caps 2, so that the blasting caps may be discharged from the liner singly (Fig. 3). Over the opening 6 may be folded the cover flap 7 which will form a continuous cover when it contacts the cover member 9 that extends over a large per cent of the top, and thus a closed box is formed. In Fig. 4, one side of the liner 1 and tin box 4 is cut away in order to show the positioning of the blasting caps 2 within the liner. It will be obvious from Fig. 4 and Fig. 3 that if the box is tilted a single blasting cap will roll from the opening 6. Further, it will be apparent that no foreign matter can possibly enter into the various blasting caps 2, since only one cap is exposed at a time and the exposure of this cap does not permit the open end thereof to be in a position such that foreign matter can fall thereinto and onto the explosive charge.

Fig. 5 is a plan view of the blank from which liner 1 is formed prior to the folding thereof to form a complete assembly. This blank comprises a rectangular bottom or base 3 from which there folds sides 12 and 14, a front 15, and a back 16. An extension flap on back 16 forms the top 9 which folds from back 16 into a position parallel with base 3 and contacts the top edge of sides 12 and 14. On sides 12 and 14, there are extension flaps 17 and 19 which fold inwardly until they are parallel to the bottom and which may be joined in any suitable manner to the upper or lower face of top 9. It will be noted that the extension flaps 17 and 19 do not extend for the complete length of the sides 12 and 14. Thus, they stop as shown by lines 20 and 21 in a manner which provides the opening 6 (Figs. 3 and 4). The top 9 and the side flaps 17 and 19 are of approximately the same length, i. e., the front edge of the top flap 9 exactly coincides or extends slightly beyond the lines 20 and 21. By this expedient the opening 6 is left for the discharge of caps 2.

An extension of the front 15 is provided to form the cover 7 for the opening 6 which is left when the flaps 9, 17 and 19 are positioned. This flap,

cover 7, is of sufficient width to fully close opening 6 when it is folded into a position parallel to the bottom 3.

When the liner is folded or formed, the various sides, bottom, top and covers may be provided at appropriate points with an adhesive to aid in formation of the completed assembly, for example, adhesive at points 24, 25 and 26 will aid in the assembling of the blank shown in Fig. 5 into liner 1.

It is essential in this embodiment that the length of the various sides, bottoms, tops, and flap extensions be coordinated in a manner that will produce a carton which provides a longitudinal opening along one edge or side just sufficiently wide for the discharge of a blasting cap when the blasting cap has its long axis parallel to the opening. For example, the section 9 could be a narrow flap and either sections 17 or 19 be extended in length to form a top for the liner.

The discharge opening is preferably formed on the top of the box. However, it is contemplated that this opening may be formed at any point in the box which is found most convenient. Thus, for example, the opening may be centered across the top, or it may be positioned on one side of the box. However, when the assembly 1 is used as a liner, and it is inserted into a supporting box, such as the tin box 4, with cover 5, it has been found most desirable to have the opening on the top so that it will not be necessary to remove the liner from the box in order to discharge blasting caps. If the assembly is made of sufficiently rigid material, it may form a box or container of its own accord and obviate the need of the tin support and in such instances the opening may be positioned at any desirable point. It is further contemplated that various types of openings may be incorporated within the tin box. Thus, if necessary, a slide may be incorporated instead of the removable cover, or if desirable, other types of openings may be used.

The advantages of protecting the cap from the introduction of any foreign material due to their positioning on the sides of the caps so that the open ends thereof are not exposed to the open air is very real and definitely increases the safety. However, other advantages are present in the liner prepared in accordance with this invention which make for efficiency, ease of packing, and ease of inspection. Thus, when the caps are packed into the liner, the box may be formed with one side thereof, for example, side 12 and flap extension 17, left as an opening to the liner, and through this opening the caps may be packed into the liner so that their open ends will face the side which will be covered by side 12. When the caps are so packed, they may be easily inspected and counted by a quick glance into their open ends and the appearance of the arrangement in the box, after which the flap 12 and extension 17 may be folded into position, and the assembled liner containing the blasting cap shells inserted into the tin box 4, the cover placed on, and the box is ready for distribution to the trade. Upon using the box, the cover 5 is removed, the cover flap 7 raised, the box tilted and the individual blasting cap 2 discharged singly as fast or as slowly as desired by the operator.

It has been found that the individual caps may be readily packed manually directly into the liner per se as described above, but that a more efficient method of packing the caps into the liner is by the use of a form or jig 30 (Fig. 6) of rigid material, such as wood, Bakelite, or other

material. The form desirably has the same interior length and width as the liner but is of about one-half the depth thereof. This shallow form allows easy transfer of the caps 2 into the liners and facilitates packing into the form 30. Inspection and counting is also facilitated. To assist in racking the caps in the jig 5, it has been found highly desirable to attach spacing members 31, such as a shim or fin to the jig 5 at one end of each odd row of caps 2 and a similar spacing member 31 (fin or shim) to the jig at the opposite end of the even row of caps. These spacing members cause the individual caps in each row to fit closely together and also they align the caps in adjacent rows so that they fit into the valleys formed by the contacting row. Reference to Figs. 4 and 6 will show that the spacing members would obviously cause neat efficient positioning.

The preferable method of packing caps therefore comprises placing caps into a jig or form 30 having spacing members 31 at opposite ends of alternate rows until the form is filled, inspecting the caps to determine whether any foreign material has fallen therein either before or after transferring this group of caps into the partly formed liner, closing the side of the liner over the caps, and inserting the filled liner into a tin or similar supporting box so that the caps have their long axes parallel to the top of the box.

Whenever the present package is in use, there is no danger of foreign matter entering the blasting cap shells, as the open ends thereof are not exposed and this improvement constitutes a definite increase in the safety of handling these highly dangerous objects.

If desirable, a slit or window may be formed in the top cover 7, 9, or 37 which will be perpendicular to the long axes of the blasting cap shells. Such a window or slit has, in some cases, been found very useful in order to quickly and easily check the contents of the box. Thus, for example, if there are only a few caps left within the box, it is quite easy to determine the exact number present or the approximate fullness of the box by a glance into the window or slit. The opening 6 does not in itself make for quick inspection of the contents of the box due to shadows formed and the fact that the caps in the box are parallel to this opening. However, a window or slit perpendicular to the long axis of the cap provides the rapid examination of the contents. It is contemplated that such a window or slit may be either left open or may be covered with a transparent material, such as for example, Cellophane, or the like, and it will be further appreciated that this window may be located at any convenient point on the box depending entirely upon the design of the opening and the entire design, and material of construction of the box.

A more easily prepared liner than shown by Fig. 5, which, while not giving the full protection afforded by the liner of Fig. 5 having the dispensing slot, does afford more protection than the prior art methods of packing may be prepared as follows:

A blank 34 (Fig. 8) similar to that shown in Fig. 5 but without the side flaps 17 and 19 is made. This blank during the packing operation is formed with flap 32 left unfolded to allow caps to be packed perpendicular to folded side 35 (Figs. 6 and 7). Placing of the caps manually or by means of a jig 30 into the liner 34, folding of the unfolded flap 32 into place and insertion of

said liner and contents into a tin box, completes an alternate assembly in accordance with the invention. When the caps are packed directly into the liner, they are packed open end up, inspected and counted before the flap 32 is folded thereover. However, when a jig is used, which is desirable, it is preferable to pack the cap open end up in the jig and inspect and count them while in the jig.

- 10 The two-piece covers 7 and 9 (Fig. 2) can, if desired, be designed as one cover flap 37 (Fig. 8) which will be hinged to one of the four sides. This type package provides protection from foreign material and allows more readily removal of any number of caps than the liner having the cover secured so that caps must be discharged singularly. The cover flaps 7 or 37 may, if desirable, have a rectangular or semicircular groove 39 cut therein (Figs. 7 and 8) to assist in opening the flap. The groove is desirably located adjacent the closed end of the cap to prevent formation of any channel into the caps' open ends.

In regard to the material of construction, it has been found that if the liner is to be used in conjunction with a metal box of normal tin can construction material, the liner may be fairly light cardboard or heavy paper. However, if the liner is to comprise the box per se, the material 25 of construction must be heavier, for example, a heavy cardboard, corrugated or laminated paper, or the like. Further, if the liner is to be used as the box per se, the side joints will, of course, be closed by means of extension flaps, tape, or 30 the like, and various means for performing such closures are contemplated and are well within the skill of the art.

In packing of the blasting caps within the container, it has been found preferable to so coordinate the width of the container with the length 40 of the cap that there is sufficient play to allow easy removal if the cover used provides a large opening or if it provides only a dispensing slot. However, it is to be appreciated that in shipping 45 caps, they should be packed tightly within the box in which they are shipped; and in order to insure tight packing and still provide means whereby the caps can easily be discharged from the container when so desired, it has been found 50 possible to insert a shim which is easily removable before discharge of the caps, either on the top of the container or along one side thereof. Such a shim gently wedges the caps into a tight 55 position without deforming the caps and accomplishes the desired purpose in a manner which fully meets all shipping regulations. Further, the liner itself may be of material of a thickness which will act as the necessary cushioning and positioning means, for example, felt or blotting paper.

Where in the specification the term "tin box" is used, it will be appreciated that the term broadly covers the metal containers used in the art and such containers may be tinned, lacquered, or otherwise protected.

What we claim and desire to protect by Letters Patent is:

1. A package of fuse blasting caps comprising 70 in combination a plurality of open-end fuse blasting caps having long longitudinal axes and stacked together with their longitudinal axes in parallel alignment; a rectangular box of flexible sheet material entirely enclosing the caps and 75 having a bottom, sides, and a top portion, said

top portion being adapted to provide a longitudinal opening with a long axis parallel to the longitudinal axes of said caps and of a size sufficient to permit lateral discharge therethrough of one of said caps, and one of said sides having a rectangular extension flap foldably extending over and closing said opening and adapted to be foldably opened; one of said sides which is perpendicular to the longitudinal axis of said opening being adapted to be foldably opened; and a substantially rigid supporting box-like structure enclosing the box, said structure having sides and a bottom integral therewith and a removable top, said top being disposed over and contiguous to the top of said box and adapted to be removed to expose said top portion and said extension flap of said box.

2. A package of fuse blasting caps comprising in combination a plurality of open-end fuse blasting caps having long longitudinal axes and stacked together with their longitudinal axes in parallel alignment; a rectangular box entirely enclosing the caps and having a bottom, sides, and a top portion, said top portion being adapted to provide a longitudinal opening with a long axis parallel to the longitudinal axes of said caps and of a size sufficient to permit lateral discharge therethrough of one of said caps, and one of said sides having a rectangular extension flap foldably extending over and closing said opening and adapted to be foldably opened; one of said sides which is perpendicular to the longitudinal axis of said opening being adapted to be foldably opened; and a substantially rigid supporting box-like structure enclosing the box, said structure having sides and a bottom integral therewith and a removable top, said top being disposed over and contiguous to the top of said box and adapted to be removed to expose said top portion and said extension flap of said box.

3. A package of fuse blasting caps comprising in combination a plurality of cylindrical open-end fuse blasting caps having longitudinal axes stacked together with their longitudinal axes in parallel alignment; a first enclosing means made of flexible sheet material entirely enclosing the plurality of caps and having a first member adapted to form a longitudinal opening in said first enclosing means with a long axis parallel to the longitudinal axes of said caps and of a size sufficient to permit lateral discharge therethrough of one of said caps, and having a second member provided with an extension flap foldably extending over and closing said opening and

adapted to be opened; one of said sides which is perpendicular to the longitudinal axis of said opening being adapted to be foldably opened; and a second enclosing means entirely enclosing and supporting the first enclosing means and having a removable closure member disposed over the first member of said first enclosing means and adapted to be removed to expose said first member and said extension flap of said first enclosing means.

4. A prepared package for open-end fuse blasting caps having long longitudinal axes which comprises means forming a substantially rigid box having sides and a bottom integral therewith, and a removable top cover; and flexible sheet means forming a box liner for the rigid box, said liner having bottom, sides, and top portion, said top portion being adapted to provide a longitudinal opening adjacent an edge of one side of the liner and being of proper dimensions to allow the discharge therethrough of a blasting cap when the blasting cap is laid with its long axis parallel to said opening, said one side having an extension flap adapted to foldably cover said opening, one of said sides which is perpendicular to the longitudinal axis of said opening being adapted to be foldably opened, said liner being enclosed and supported by said rigid box with the top cover of said box disposed over and contiguous to the top portion of said liner.

5. A prepared package for open-end fuse blasting caps having long longitudinal axes which comprises in combination a rectangular box of flexible sheet material having a bottom, sides, and a top portion, one of said sides adapted to be foldably opened to provide a side opening and foldably closed to close said side opening, said top portion being adapted to provide a longitudinal top opening with greater dimensions than the longitudinal cross section dimensions of one of said blasting caps and with the longitudinal axis of said opening being perpendicular to said side adapted to be foldably opened, another one of said sides having an extension flap adapted to foldably cover said top opening; and a substantially rigid, rectangular, box-like structure entirely enclosing and supporting the box, said structure having sides and a bottom integral therewith and a removable top, said top being disposed over and contiguous to the top portion and extension flap in closed position of said box.

ALBERT R. ELY.
ROSCOE B. SMITH.
